LOOM

Erlaf Groetschel, Berlin, Germany

Application September 28, 1938, Serial No. 232,089
In Germany July 16, 1937

15 Claims. (Cl. 139—29)

This invention relates to looms with vertical warp threads and provides means for effecting the drive such as are mainly employed in looms of the domestic or household type.

5 The invention resides more particularly in the fact that a plurality of warps situated one behind the other in vertical planes and freely accessible from both sides are passed through an upwardly and downwardly oscillating reed frame. The actuating and control members for the cloth take-up, for the heald movements, for the shuttle movement and also for the oscillating reed frame are designed on the lines of a domestic loom and can be operated, while deriving 10 the drive from a main shaft, without any substantially greater expenditure of power than in the case of domestic looms with only one web of cloth. The movements of the actuating and control members are effected by way of a main 15 shaft, for example from a pedal crank drive arranged separately of the loom in a saddle bracket or the like.

The shuttle boxes may be connected to the reed frame oscillating up and down under the 20 action of an eccentric or connecting-rod crank drive, or may be arranged stationarily independently of said reed frame. In the case of stationary shuttle boxes a common picking motion actuated by separate control means is preferably provided, whilst in the case of oscillating shuttle boxes the picking plates are tensioned by the upward and downward movement of the reed frame.

For controlling the harness frames, the cloth 25 take-up motion and the conjointly moved picking plates a lay-shaft preferably having interchangeable tappets, notched discs and the like is provided, which is actuated from the main driving shaft.

30 The different parts of the loom are arranged in such fashion that they are simultaneously accessible from all sides, and so that a plurality of, for example three, looms are combined in one frame with a common drive. The reed frame 35 provided for all webs of cloth is suspended from equalising springs for the purpose of reducing the driving power required, the said springs being so designed that they simultaneously assist the tensioning of the picking plates.

40 Several embodiments of the loom according to the invention are illustrated by way of example in the accompanying drawings, wherein

Fig. 1 shows diagrammatically an elevational view of a loom for producing three fabrics.

45 Fig. 2 is an end view corresponding to Fig. 1.

Fig. 3 is a perspective view of the more important actuating and control members for the formation of the shed, the take-up of the cloth and other functions.

Fig. 4 is a perspective view of a shuttle box 5 with the picking plate tensioning device.

Fig. 5 is a longitudinal section through a shuttle box.

Fig. 6 is a perspective view of a shuttle, and

Fig. 7 shows the releasing means for the picking plate locking members in front view.

Fig. 8 is another embodiment of a loom according to Fig. 1, having a stationary picking mechanism.

Fig. 9 is a part view of a shuttle box of the 15 loom according to Fig. 8.

In the vertical uprights 1 of the loom a reed frame 3 common to warp groups 2 situated one behind the other in three vertical planes is guided by means of rollers 4 or the like so that 20 it can oscillate up and down in a vertical direction.

The warp threads 2 are let off the warp beams 5 mounted in the lower part of the loom, then pass through common healds or harness frames 25 7, 8 adapted to slide in lateral grooved guides 6 and thereupon enter the reed frame 3. In the plane of the warp threads 2 the reed frame 3 has reeds of known design, which are simultaneously adapted for guiding the shuttles 9. 30 The adjoining web of cloth then passes in the upper part of the loom over take-up rollers 10 and is wound on cloth rollers 12, which bear against the take-up rollers by the action of springs 11. The bearings 13 for the cloth rollers 12 are mounted on pivots 14. Owing to this 35 pivotal mounting and also the provision of the springs 11 the cloth rollers 12 are always caused to bear against the take-up rollers 10, irrespective of the fact as to whether there is much or 40 little cloth on the rollers 12.

The drive for all component parts of the loom is derived from a main shaft 15. Since in accordance with the invention the operation of the various actuating and control members does 45 not require any substantially greater expenditure of power than in the case of domestic looms having one web of cloth, the main shaft can advantageously be rotated by a pedal crank drive 17 mounted separately from the loom in a saddle bracket 16 and acting through the medium of a belt 18, a chain or the like. The rotation of the main shaft 15 is transmitted by means of belts 21, 22, chains or the like to two shafts 19, 50 preferably mounted in the vicinity of the upper 55

rights 1. Mounted on one end of the shafts 19, 20 are crank discs 23, 24 pivotally connected to the reed frame 3 by connecting rods 25. The reed frame 3 is thereby moved evenly up and down at four points in the uprights 1 by the connecting-rod crank drive 23, 24, 25, its stroke corresponding to the diameter of the discs 23, 24.

The shaft 20 carries a ratchet finger 26, which intermittently rotates a lay-shaft 27 through the medium of a star wheel 28 (Fig. 3). Mounted on the lay-shaft 27 are tappets 29 co-operating with a double-armed lever 31 pivoted at 30. The lever 31 has a slot 32 in which a connecting piece 33 for a pull member 34 is adapted to slide and to be secured in certain location (Fig. 1). At its other end the pull member 34 is secured to a second connecting piece 35 adapted to slide and to be clamped in a suitable shaped slot 36 in a one-armed lever 37. The lever 37, which is mounted in the upper part of the loom, is adapted to rock about the axis 38 and is drawn continuously by the spring 39 in the direction of the stop 40. Due to the rotation of the tappets 29 the lever 31 and, through the medium of the member 35, the lever 37 is rocked at certain intervals against the action of the spring 39; that is to say, a pull in the direction of the arrow α is exerted periodically on the member 34. During the rocking movements of the lever 37 its pawl 41 drives a ratchet wheel 42, which is secured against backward rotation by a locking pawl 43. The intermittent movement of the ratchet wheel 42 is transmitted to a sprocket wheel 44 mounted with it on the same shaft 38. A chain 45 passes about the wheel 44 and also about further sprocket wheels 47 secured to the shafts 46 of the take-up rollers 10, so that all wheels 47, and hence the take-up rollers 10, are rotated in the same direction by the wheel 44. Tensioning rollers 48 ensure the position of the chain 45 on the wheels 47. The parts 29, 31, 37, 42, etc., are so adjusted relatively to one another that unobstructed fabric take-up corresponding to the pick of the weft is ensured, variation of the fabric take-up being quite readily possible within certain limits by means of the parts 33, 35.

Notched discs 49 for the attachment of tappets 50 are mounted on the lay-shaft 27 according to the weave required and the existing healds 7, 8. According to the number of the notched discs 49 present, double armed levers 52 are pivotally mounted on a spindle 51. The rocking movements of the levers 52 depend upon the size of the tappets 50. The free ends of the levers 52 are connected to the healds 7, 8 by flexible pull members 53. According to the position of the tappets 50 on the lay-shaft 27, the levers 52 are rocked at uniform intervals of time, and hence the healds 7, 8 through the medium of the pull members 53 are caused to slide in the guides 6 against the action of tension springs 54 (Figure 1) for forming the shed.

Picking of the shuttles takes place simultaneously for all the warp groups 2 by means of the picking device shown in Figure 4. Shuttle boxes 55 substantially comprising two vertical walls 56 are fixed to the reed frame 3 in line with the individual reeds. The closure of the box 55, which is open towards the reed, is formed by a picking plate 57 adapted to slide on the box bottom 58. It is guided by lateral rods 59 secured to it and passing through eyes 60 fixed externally of the walls 56. Tension springs 61 tend to press

the plate 57 constantly against the front edges of the walls 56. Fixed to the shuttle box bottom 58 are arms 62 forming the pivots 63 for a bell-crank system 64. Pivotally connected at 68 to the bell-crank system 64 of each shuttle box 55 is a knee lever 67 connected by hinges 65 to longitudinal members 66 of the loom. The free arms 69 of the bell-crank lever 64 bear against rollers 70 mounted on the picking plate 57.

When the reed frame 3 is in its lowest position, 10 the shuttle boxes 55 are closed and the knee levers 67 are in a substantially vertical position (Figures 2 and 4). When the reed frame moves upwardly, the knee lever 67 are obliged to yield and bend towards the inside of the loom owing to 15 their hinged suspension. The bell-crank systems 64 are thereby also turned outwardly, as indicated in chain lines in Figure 2, the arms 69 pressing back the rollers 70 and hence the picking plates 57 of the individual shuttle boxes 20 against the action of the springs 61, until they move behind resilient locking noses 71 projecting through the shuttle box bottom 58. Each locking nose 71 is situated on the end of a double 25 armed lever 72 which is pivoted to the bottom 58 at 73 and is under the action of the spring 74. For picking the shuttles 9 it is merely necessary to turn the lever 72 so that the locking nose 71 releases the picking plate 57 which under the action of the springs 61 propels the shuttle 9 into 30 the opposite shuttle box.

A control device as shown in Figure 7 is provided on each side of the loom for rocking the levers 72. This device in the constructional example shown, in accordance with the warp groups 35 present, comprises three one-armed levers 75 adapted to be rocked about the pivots 76 into the chain line position under the action of the spring 71. Their movements in common are ensured by a connecting rod 78 pivotally connected to them. When the levers 75 are in the vertical position, the free ends of the double armed levers 72 situated on one side of the reed frame strike against the upper edges of said levers 75 during the descent of the reed frame 3. During 45 the further descent of the reed frame, therefore, the pawls 71 are withdrawn from the path of the picking plates 57 and simultaneous picking of all the shuttles of one side takes place. During 50 this operation, however, the levers 75 provided on the opposite side of the loom are in the outwardly rocked position, so that no release of the picking plate 57 can take place.

For the alternate rocking of the picking plate control members 75, 76, 77, 78, two tappet rings 55 79 are fixed to the lay-shaft 27, said rings being offset relatively to one another and co-operating with two rocking levers 80. The alternating movements of the levers 80 are transmitted by pull members 81 through suitably arranged rollers to the picking plate control members 75, 76, 77, 78.

In order, despite its increased efficiency, to be able to provide the loom with a common hand, foot or the like drive, the reed frame 3 is suspended for example from eight equalising springs 82, the strength of which is such as to correspond substantially to the sum of the loads resulting from the weight of the reed frame 3 and the power of the picking plate tension springs 61 70 and of the other tension springs employed.

As shuttle catching device there is advantageously employed a lever 84 under the action of the spring 83 and pivoted to the picking plate 57. The lever 84 has a locking nose 85 adapted 75

to engage behind an upwardly projecting yoke 86 on the shuttle 9. The catch lever 84 is furthermore provided with a sloping slide surface 87 and its front end is guided in a rail 88 secured 5 to the shuttle box walls 56. The rail 88 however does not project into the path of the shuttle yoke 86. The shuttle propelled into the box 55 rebounds against the picking plate 57 provided with suitable coverings. It cannot be projected 10 out of the box again, however, under the action of the rebound, because the locking nose 85 has passed behind the yoke 86. Upon the release of the picking plate 57, the catch lever 84 moves with it in the same direction, and its slide surface 15 15 face 87 abuts against the rail 88, whereby it is rocked automatically so that its nose 85 releases the shuttle 9.

According to Figure 8, a disc 89 embraced by an eccentric 90 is fast on the driving shaft 15. 20 The eccentric 90 is fixed to the reed frame 3 and is thus moved vertically up and down by the rotation of the shaft 15 or disc 89.

On both sides of the reed frame 3 are provided stationary, that is, non-oscillating, picking rails 25 91 for all three or six shuttle boxes 55 (Figure 9). Springs 92 tend to press the continuous rails 91 against the picking plates 57 of the shuttle boxes 55. A pull member 93 which passes over the rollers 94, 95 and is secured to a lever 96 30 brings the picking rails 91 into the respective tensioned position. In order to effect the tensioning and release of the continuous picking rails 91 on both sides, there are provided on both ends of a shaft 97 cams 98 which have their 35 rises offset relatively to one another, so that the levers 96 permanently co-operating with the cams 98 by means of the rollers 99 are depressed alternately. The picking rails 91 are consequently retracted by means of the pull members 93 40 and the springs 92 are tensioned. Upon each rotation of the cam 98, the roller 99 drops once behind the rise 100, the springs 92 being released and the picking rails 91 striking against the plates 57 or shuttles 9. The rotation of the 45 shaft 97 is transmitted from the driving shaft 15 by means of a spur wheel mechanism 101, 102. If the springs 61 are omitted the plates 57 may serve as shock absorbers and may be provided with a leather covering or the like in known 50 manner. Preferably, each reed or shuttle guiding rail 103 of the frame 3 is adapted to be turned on hinges 114 and fixed in position by push-in pins 115 or the like.

Secured to the reed frame 3 are one or more 55 pull members 106 attached to a cross-bar 104. Pivotally connected to the bar 104 are arms 105 on which are mounted pawls 106. The arms 105 are held in position by pull members 107 with equalising springs 108. Each pawl 106 co-operates 60 with a ratchet wheel 109. As is indicated in Figure 8, the movements of the ratchet wheels 109 are transmitted to the rollers 10, each of which is connected to the associated cloth roller 12 by a belt or chain 110. The movement of the 65 rollers 10 or cloth rollers 12 is thus effected in the same timing as the upward and downward movement of the reed frame 3. Upon each descent of the frame 3 the arms 105 are moved 70 downward, thus producing the feeding movements or rotation of the members 109, 10 and 12 connected thereto. As the reed frame 3 on its upward and downward movement travels over a greater distance than is permitted by the rotation 75 of the rollers 10, 12, length equalising ele-

ments in the form of tension springs 111 are provided in the pull members 106.

With the omission of the lay-shaft 27, the actuation of the harness frames or healds 7, 8 is effected according to Figure 8 for instance by 5 means of a card device 112 known per se in the case of looms.

In the constructional example of the invention according to Figures 8 and 9, the shuttle boxes 10 55 may also move up and down with the reed frame 3. The configuration of the common stationary picking mechanism 91, 93, 96, 98, however, also permits of a stationary arrangement of the shuttle boxes 55.

The invention provides a loom to be equipped 15 if desired with hand or foot drive which, with substantially the same expenditure of power, renders possible a double, triple or multiple output as compared with the domestic looms known heretofore with only one web of cloth, and at the 20 same time, the production of all the cloth webs can be supervised from all sides. Consequently, all the components are also readily accessible, for instance for eliminating stoppages. All the important actuating and control members are 25 combined in a clear manner on a common lay-shaft. By the use of notched discs for the interchangeable fixing of the tappets for actuating the healds, the otherwise usual card control or any other complicated control device for producing 30 the desired weave is dispensed with. Despite the simple construction of the loom, the adjustment of the cloth take-up, the actuation of the healds and so forth may be varied as desired in accordance with the nature of the cloth to be manufactured. Due to the fact that not the cloth rollers but the take-up rollers provided with a rough 35 surface are driven and the cloth rollers are pressed against these take-up rollers, it is possible to secure a constant take-up roller drive despite 40 the increasing cloth roller diameter.

The invention according to the two constructional examples described eliminates all the disadvantages necessarily encountered heretofore in 45 looms for producing a plurality of webs of cloth, as compared with those for one web of cloth. The construction has been considerably simplified, a much less powerful drive being thereby necessary. Whereas, due to the counterwise 50 cloth take-up in the case of looms having a plurality of vertical webs of cloth, warp threads are necessarily situated immediately one behind the other, in the case of the invention they are freely accessible from both sides. The actual weaving 55 operation takes place in the same plane for all fabrics, and thereby supervision of the loom for thread breakage, weaving faults and so forth is considerably simplified. The movement of all the components can be supervised and their function 60 is readily understood. The subject of the invention is therefore excellently adapted for use for instructional purposes.

What I claim as new and desire to secure by 65 Letters Patent is:

1. In a loom of the character described, an upwardly and downwardly oscillating reed frame provided for warps situated one behind the other in vertical planes and freely accessible from both sides, equalising springs on which the said reed 70 frame is suspended, shuttle picking plates tensioned by the said reed frame upon its upward movement, and a connecting rod crank mechanism for producing the upward and downward movement of the said reed frame. 75

2. In a loom of the character described, an upwardly and downwardly oscillating reed frame provided for warps situated one behind the other in vertical planes and freely accessible from both sides, equalising springs on which the said reed frame is suspended, shuttle picking plates tensioned by the said reed frame upon its upward movement, and an eccentric drive for producing the upward and downward movement of the said reed frame.

3. In a loom of the character described, an upwardly and downwardly oscillating reed frame provided for warps situated one behind the other in vertical planes and freely accessible from both sides, shuttle guides and reeds pivotally mounted on hinges on the said reed frame, a pull member acted upon by the said frame and a lever system to move the cloth rollers of the loom intermittently in the same direction, and a stationary picking mechanism for moving all of the shuttles of the loom.

4. In a loom of the character described, an upwardly and downwardly oscillating reed frame provided for warps situated one behind the other in vertical planes and freely accessible from both sides, shuttle guides and reeds pivotally mounted on hinges on the said reed frame, a pull member acted upon by the said frame and a lever system to move the cloth rollers of the loom intermittently in the same direction, and picking plates mounted on the oscillating reed frame for moving all of the shuttles of the loom.

5. In a loom of the character described, an upwardly and downwardly oscillating reed frame provided for warps situated one behind the other in vertical planes and freely accessible from both sides, shuttle guides and reeds pivotally mounted on hinges on the said reed frame, a pull member acted upon by the said frame and a lever system to move the cloth rollers of the loom intermittently in the same direction, means for equalising the length of the said pull member, and a common picking mechanism for moving all of the shuttles of the loom.

45 6. In a loom of the character described, an upwardly and downwardly oscillating reed frame provided for warps situated one behind the other in vertical planes and freely accessible from both sides, shuttle boxes on the said reed frame, picking plates serving as closures for the said shuttle boxes, locking projections for the said picking plates, and a knee lever and bellcrank system for pressing the said picking plates against the action of tension springs behind the said projections during the upward movement of the said reed frame.

7. In a loom of the character described, an upwardly and downwardly oscillating reed frame provided for warps situated one behind the other in vertical planes and freely accessible from both sides, equalising springs on which the said reed frame is suspended, shuttle boxes on the said reed frame, picking plates serving as closures for the said shuttle boxes, locking projections for the said picking plates co-operating with picking plate tension springs, and a knee lever and bellcrank system for pressing the said picking plates against the action of the said tension springs behind the said projections during the upward movement of the said reed frame, the said equalising springs corresponding to the sum of the forces resulting from the weight of the said reed frame and the force of the said tension springs.

75 8. In a loom of the character described, an up-

wardly and downwardly oscillating reed frame provided for warps situated one behind the other in vertical planes and freely accessible from both sides, shuttle boxes on the said reed frame, picking plates serving as closures for the said shuttle boxes, locking projections for the said picking plates, means for moving the said picking plates behind the said projections, tappets for effecting the forward movement of the cloth rollers of the loom, tappets for alternate retraction of the said picking plates and for actuating the healds of the loom, a lay-shaft bearing the said tappets, and a connecting-rod crank mechanism for intermittently rotating the said lay-shaft.

9. In a loom of the character described, an upwardly and downwardly oscillating reed frame provided for warps situated one behind the other in vertical planes and freely accessible from both sides, shuttle boxes on the said reed frame, picking plates serving as closures for the said shuttle boxes, locking projections for the said picking plates, tappets for alternate retraction of the said picking plates and for actuating the healds of the loom, a lay-shaft bearing the said tappets, and notched discs mounted on the said lay-shaft for interchangeable attachment of the said tappets.

10. In a loom of the character described, a loom frame, an upwardly and downwardly oscillating reed frame provided for warps situated one behind the other in vertical planes and freely accessible from both sides, cloth rollers on the said loom frame, take-up rollers on said loom frame bearing by spring action against the said cloth rollers, and a ratchet wheel and chain drive actuating the said take-up rollers in common.

11. In a loom of the character described, an upwardly and downwardly oscillating reed frame provided for warps situated one behind the other in vertical planes and freely accessible from both sides, shuttle boxes on the said reed frame, picking plates serving as closures for the said shuttle boxes, an elevated yoke on each shuttle, and a resilient catch lever on each picking plate adapted to engage with the said yoke.

12. In a loom of the character described, an upwardly and downwardly oscillating reed frame provided for warps situated one behind the other in vertical planes and freely accessible from both sides, shuttle boxes on the said reed frame, picking plates serving as closures for the said shuttle boxes, an elevated yoke on each shuttle, a resilient catch lever on each picking plate adapted to engage with the said yoke, and a rail fixed to each shuttle box, the said catch lever being guided by means of a sloping slide surface in the said rail.

13. In a loom of the character described, an upwardly and downwardly oscillating reed frame provided for warps situated one behind the other in vertical planes and freely accessible from both sides, shuttle boxes, a stationary shuttle picking mechanism, means for driving the said reed frame in common with the cloth rollers of the loom, means on either side of the loom for driving the said picking plates common to all of the said shuttle boxes, and gear wheels coupling the said frame drive to the said picking plate drive.

14. In a loom of the character described, an upwardly and downwardly oscillating reed frame being supported in a state of balance and provided for warps situated one behind the other in vertical planes and freely accessible from both sides, shuttle picking plates tensioned by the said reed frame upon its upward movement, and a

connecting rod crank mechanism producing the upward and downward movement of the said reed frame.

15. A loom, comprising a loom frame, a plurality of warp beams and cloth take-up rollers mounted in pairs substantially vertically above one another upon said loom frame, the warps

being situated one behind the other in a plurality of vertical planes and freely accessible, a common reed frame through which said warps pass and means for reciprocating said reed frame in a vertical direction and supporting it in a state of balance.

ERLAF GROETSCHEL.
